RAY P. JACKSON, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

INSULATOR.

1,191,186.

Specification of Letters Patent. Patented July 18, 1916.

Application filed December 21, 1910. Serial No. 598,515.

To all whom it may concern:

Be it known that I, RAY P. JACKSON, a citizen of the United States, and a resident of Edgewood Park, in the county of Allegheny and State of Pennsylvania, have invented a new and useful Improvement in Insulators, of which the following is a specification.

My invention relates to insulators, and it has special reference to devices of this character that severally comprise a plurality of vertically arranged sections fitted one within another.

The object of my invention is to provide a device of the above-indicated character which shall be simple and durable in construction, and shall embody adequate means for preventing heavy leakage currents and consequent excess static "fringing" over the surface of the insulator.

Another object of my invention is to provide an insulating device which shall be constructed of a plurality of identical sections so formed as to be readily assembled.

The advantage of such a structure, of course, resides in the economy which may be effected by reason of the fact that each section is of standard size and pattern. Furthermore, the number of separate sections determines the electrical strength of the insulator, and it is, therefore, a simple matter to design and construct an insulator for any desired voltage, within reasonable limits.

In the prior art, it has been common practice to build multi-section insulators, the component sections of which have been cemented together for the purpose of providing a rugged and integral structure. However, when such insulators have been constructed, the individual sections have been of such form and have been assembled in such a manner that the usual flaring petticoat portion of each section has been located below the layer of cement which secured that section to the adjacent lower section. It is well known that cement is a good conductor, as compared with porcelain, and hence it is obvious that in a multi-section porcelain insulator of the type indicated, the various layers of cement and interposed porcelain constitute a series of condensers. For mechanical reasons, in certain types of insulators, the layers of cement have not been disposed opposite one another, but have been slightly overlapped or entirely offset, so that

there existed abnormal and excessive leakage current and static "fringing" over the surface of the insulator from one layer of cement to another. This concentrated "fringing" resulted in a particularly severe 60 and unstable electro-static condition over the insulator surface in proximity to the layers of cement and the air immediately surrounding the insulator became ionized and its dielectric strength so weakened and 65 broken down that a discharge was effected. It is evident that if these layers of cement were opposite each other, as in the usual type of condenser, no such unstable conditions of leakage current and static "fringing" would have existed, as the charges of 70 opposite sign would have neutralized each other. However, for mechanical strength the offset disposition of the cement layers is desirable, and it is to establish quiet and 75 stable static conditions and to eliminate this leakage current and its disastrous effects, without changing the mechanical design of the insulator, that my present invention is intended.

According to my invention, I design the insulator sections so that the flaring petticoat portion of each section shall be located above the cement layer which is interposed between the section and the adjacent lower 85 section, when the insulator, as a whole, is finally assembled. Thus, a relatively long path is provided for the leakage current in traversing from one cement layer to the next, which tends to materially reduce the leakage 90 current and to cut off the localization of excessive static "fringing". Hence, the dielectric properties of the enveloping air are not subjected to abnormal stress and a premature breakdown over the insulator is 95 avoided.

Those skilled in the art will readily understand that the principle of my invention may be embodied in various structural devices and, while I shall show and describe, in detail, only a single embodiment of my invention, it is evident that, broadly considered, it is not restricted to the specific structure hereinafter set forth.

The single figure of the accompanying 105 drawing is a view, partially in vertical section and partially in side elevation, of a device constructed in accordance with my invention.

Referring to drawing in detail, the multi- 110

2

section insulator shown comprises a plurality of interchangeable porcelain insulator sections 1 and 2 which are vertically arranged and nested the one within the other, and which are provided with a suitable metallic cable unit 3 and supporting pin 4. The insulator sections 1 and 2 are identical in size and form and each comprises a tapered plug or cap portion 5 having a corrugated exterior surface, a flaring petticoat section 6, and a body portion 7 of the same general taper as the plug portion 5. The top 5^a of each plug portion 5 forms a top-closure diaphragm, separating the air spaces of the vertically adjacent sections.

15 The body portion 7 and the plug portion 5 are provided with a centrally located recess, the lower portion 9 of which is corrugated in the usual manner and is adapted to receive the plug portion 5 of the insulator section next below it. The upper portion 10 of the central recess is adapted to receive a pin or plug 11 of wood or other suitable insulating material which comprises a body member 12 and an integrally associated head member 13. The head member 13 fits reasonably tight within the recess and is adapted to rest upon the upper end of the plug or cap portion 5 of the adjacent lower insulator sections in order to properly space the several sections apart, maintain the same in their relative positions under all conditions, and prevent the entry of cement into the space between the heads of juxtaposed units, which might otherwise occur if cement is supplied between the heads of the adjacent units while they are supported in inverted position by the pins 12. The insulator sections 1 and 2 are thus assembled, 40 one above another, and are intimately secured together by means of a layer or band of cement 14 which is interposed between the co-operating plug portion 5 of section 2 and the body portion 7 of section 1.

45 The upper insulator section 1 is provided with the metallic cap 3 which is held in place by a layer of cement 15 for the purpose of receiving a line conductor (not shown), while the lower section 2 is mounted 50 upon the supporting pin 4 and is secured thereto by a layer or band of cement 16 in a manner similar to that hereinbefore described. Since cement is a comparatively good conductor, it is evident that the layers 55 of cement 14, 15 and 16 and the interposed porcelain portions constitute a series of condensers, the plates of which are not opposite each other as in the usual condenser construction, but are entirely offset.

60 Assuming, for the moment, that the insulator sections 1 and 2 are not provided with petticoat portions 6, it will be understood that the electric field will be concentrated between the edges of the offset condenser plates 14, 15 and 16 and a leakage

current will flow which produces an excessive static "fringing" between the plates, tending to neutralize each other. This excessive leakage current is caused by reason of the abnormal positions of the condenser plates 14, 15 and 16, and the resulting static "fringing" intensifies the usual electrostatic field, and acts upon the surrounding air to break down its dielectric strength to such an extent that a discharge is effected over 75 the surface of the insulator. It is the purpose of my invention to eliminate this abnormal leakage current and static "fringing" so that the dielectric properties of the surrounding air may be utilized to their full 80 extent. This I accomplish by locating the petticoat portions 6 above the lower portion 9 of the centrally located recess which receives the plug portion 5 and the interposed layer of cement 14 or 16. It is manifest, 85 therefore, that a considerable increase in the length of the path of the leakage current is provided which reduces the amount of current and also tends to cut off the excessive static "fringing" hereinbefore described. 90

The specific structural details of the device heretofore shown and described may, of course, be varied and the materials of construction changed, without exceeding the spirit and scope of my invention. 95

I claim as my invention:

1. The combination with a plurality of identical insulator sections arranged vertically, one within another and secured together by longitudinally spaced layers of cementing material, each section comprising a cap portion and a body portion having centrally disposed communicating recesses therein and an outwardly flaring petticoat portion located above the upper end of its 105 inclosed layer of cementing material, of a spacing pin of insulating material disposed in the recess in said cap portion and adapted to rest against the upper end of the projecting cap portion of the adjacent lower 110 section.

2. A built-up insulator comprising interchangeable, nested units, top-closure diaphragms for each of said units, said diaphragms being spaced apart and serving to 115 form inclosed air chambers together with a cap unit formed to receive an electric cable, the bottom unit receiving the supporting pin.

3. A built-up insulator, having nested 120 units, in combination with means for spacing said units apart and preventing the entry of cement into the space between the heads of juxtaposed units.

4. A built-up insulator having nested 125 units, the heads of which are air-spaced apart, in combination with means for preventing the entry of cement into said air space during the assembly of the parts.

5. A built-up insulator having nested 130

units, the heads of which are air spaced apart, in combination with means supporting a nested unit during assembly in inverted position and excluding cement from 5 said air space.

6. A built-up insulator comprising nested units, top-closure diaphragms for the said units, said diaphragms being spaced apart from one another, and means for preventing

the entry of cement into the space between 10 adjacent diaphragms.

In testimony whereof, I have hereunto subscribed my name this 9th day of Dec. 1910.

RAY P. JACKSON.
